[57] ABSTRACT

The improvement in a process for the production of alpha,omega-alkanedioic acid of 10 to 14 carbon atoms in a mixture comprising n-alkane of 10 to 14 carbon atoms, culture medium and a mutant of *Corynebacterium* capable of producing at high yield and conversion alpha,omega-alkanedioic acid which comprises operating the process in the presence of an inducer, i.e., a blend of substantially branched saturated aliphatic hydrocarbons of 12 to 22 carbon atoms, the blend having a boiling point of from 150° to 255°C. and/or a blend of n-alkanes having from 15 to 24 carbon atoms with the proviso that initially the ratio of volume of the inducer to the n-alkane of 10 to 14 carbon atoms is from 3:1 to 1:3 and the volume of the n-alkane of 10 to 14 carbon atoms is from 1 to 50 percent of the total volume of the culture medium, and n-alkane of 10 to 14 carbon atoms.

7 Claims, No Drawings

PROCESS FOR THE BIOLOGICAL PRODUCTION
OF ALPHA, OMEGA-ALKANEDIOIC ACID

This invention relates to an improved process for the production of alpha, omega-alkanedioic acid from n-alkanes through the use of mutants of *Corynebacterium*. Particularly, this invention relates to utilizing an inducer in the process during the fermentation, the inducer comprising substantially branched saturated aliphatic hydrocarbons of 12 to 22 carbon atoms and/or a blend of n-alkanes of 15 to 24 carbon atoms.

It is known that alpha,omega-alkanedioic acid can be prepared by allowing mutants of *Corynebacterium 7E1C*(ATCC-19067) to ferment with n-alkanes. Processes which have been utilized for such fermentation have not achieved commercially attractive yields and conversions of acid. Therefore, improvement in the processes was required to improve such yields and conversions.

Such an improvement has been found. The improvement comprises operating the process for the production of alpha,omega-alkanedioic acid of 10 to 14 carbon atoms in a mixture comprising n-alkane of 10 to 14 carbon atoms, culture medium and a mutant of *Corynebacterium* capable of producing alpha,omega-alkanedioic acid at high yields and conversions in the presence of an inducer selected from the class consisting of a blend comprising substantially branched saturated aliphatic hydrocarbons of 12 to 22 carbon atoms, the blend having a boiling point of from 150°-255°C., a blend comprising n-alkanes having from 15 to 24 carbon atoms and mixtures thereof with the proviso that initially the ratio of the volume of the inducer to the n-alkane of 10 to 14 carbon atoms is from 3:1 to 1:3 and the volume of the n-alkane of 10 to 14 carbon atoms is from 1 to 50 percent of the total volume of the culture medium and n-alkane of 10 to 14 carbon atoms.

The preferred amount of n-alkane of 10 to 14 carbon atoms present relative to the total volume of the culture medium and n-alkane of 10 to 14 carbon atoms is from 5 to 20 percent by volume. The preferred ratio of the inducer to the n-alkane of 10 to 14 carbon atoms is about 1:1 by volume.

A preferred inducer is the blend of substantially branched saturated aliphatic hydrocarbons of 12 to 22 carbon atoms, in particular, a blend comprised mainly of hydrocarbons of at least 14 carbon atoms. The preferred blend boils at from 196° to 250°C. A preferred blend of n-alkanes is a blend of n-alkanes of at least 16 carbon atoms.

A culture medium which is useful in the present invention is aqueous and comprises 1) 3 to 35 grams per liter of a member selected from the class consisting of alkali metal nitrate, calcium nitrate, magnesium nitrate, strontium nitrate, beryllium nitrate and mixtures thereof; 2) a 0.3 to 10 grams per liter of alkali metal phosphate; 3) 1 to 15 grams per liter of an alkali metal acetate, calcium acetate, magnesium acetate, strontium acetate, beryllium acetate and mixtures thereof; 4) a nutrient source.

The amount of metal nitrate utilized in the culture medium depends on the mutant of *Corynebacterium* which is used. A relatively large amount of nitrate is required for the bacteria utilizes it as the sole source of nitrogen. Preferably 6 to 30 grams per liter of the metal nitrate is present in the culture medium. The preferred nitrates are the alkali metal nitrates, in particular so-

dium or potassium. The most preferred concentration of the metal nitrate in the culture medium is 12 to 25 grams per liter.

The alkali metal phosphate is used as a buffer component in the culture medium. A sufficient amount of the phosphate is present in the culture medium to cause it to have a pH of from 6 to 9. Therefore, the amount utilized will vary according to the other components in the culture medium. The preferred amount of alkali metal phosphate in the culture medium is 1 to 6 grams per liter. Preferred phosphates are K_2HPO_4 and $NaH_2PO_4 \cdot H_2O$.

The metal acetate is critical as a component in the culture medium in that it significantly increases the yield of the alpha,omega-alkanedioic acid when the culture medium is used in the process of this invention. The preferred concentration for the metal acetate is from 2.5 to about 10 grams per liter. Preferred acetates are the alkali metal acetates, in particular, sodium and potassium.

The type of nutrient source in the culture medium is not critical. Examples of useful nutrient sources are tomato juice broth solids, molasses plus yeast extract or cottonseed meal. The first two types of nutrient source are preferred. The amount of nutrient source utilized is normally from 1 to 5 grams per liter, preferably around about 2 grams per liter of the culture medium.

The balance of the culture medium is made up of water. This can be tap water or distilled water. Other components can be present in the culture medium if they do not impede the function of the main components. Some of such components are $MgSO_4 \cdot 7H_2O$, $CaCl_2$, (neither of these two should be used in large amounts or they may cause the phosphate to precipitate), $FeSO_4$ with ethylenediamine tetraacetic acid chelating agent, $MnSO_4 \cdot H_2O$, H_3BO_3 , $Na_2MoO_4 \cdot 2H_2O$, KI , and $ZnSO_4 \cdot 7H_2O$. It is preferred that no ammonium compounds be present for they erode the ability of the medium to cause the bacterium to accumulate acid. Copper compounds can be included in the medium. However, they tend to give no advantage but instead result in reduced acid production.

The culture medium can contain emulsifier. This is not required but does normally render the culture medium more conducive to manipulation. Useful emulsifiers are substances such as "Ethofats" (Armour and Company, Chicago, Illinois) which is monofatty or rosin acid esters of polyoxyethylene glycols having the general formula

Examples of other nutrient type additives which can be included in the culture medium are amino acids, vitamins, glucose, sugar, adipic acid, butyric acid and glutaric acid.

The culture medium which is discussed above is the medium which is used in the process for preparing the alpha,omega-alkanedioic acid in the full scale fermentation but is normally not used in the pregrowth of the bacteria. Pregrowth of the bacteria can be accomplished by placing a lyophile culture of freeze-dried bacteria on a tomato juice agar slant which contains proteins and carbohydrates, i.e., tomato juice extract and glucose. The bacteria grows for from 24 to 48 hours at 37°C. on the slant. A loopful of the bacteria is

then transferred to a large flask such as a 125 ml. Erlenmeyer for pregrowth. In the pregrowth stage the bacteria normally grows on a solution comprising 5 weight/volume percent molasses, preferably cane, 0.5 weight/volume percent yeast extract, 0.15 weight/volume percent K_2HPO_4 , 0.06 weight/volume percent $NaH_2PO_4 \cdot H_2O$ and water. Weight/volume percent means grams/milliliters in percent terms, i.e., 5 grams in 100 mls. is 5 weight/volume percent.

The pregrowth flask is maintained at about 37°C. and vibrated at 220 rpm's. on a shaker with a 1 inch throw for 24 hours. The volume of the material in the initial pregrowth flask is normally 25 ml. although this is not critical. The pregrowth medium plus bacteria is built up by successive spiking of larger and larger volumes. When a pregrowth volume is obtained which is about 10 percent of the total volume of materials to be used to make the alpha,omega-alkanedioic acid, the pregrowth stage is completed. At this point, the pregrowth medium should contain at least 1×10^9 organisms per ml. Normally, all the pregrowth medium is used to inoculate the culture medium and n-alkane.

The invention involves an improvement of the normal process for the production of alpha,omega-alkanedioic acid. The normal process for the production of alpha,omega-alkanedioic acid of 10 to 14 carbon atoms comprises (1) introducing a mutated strain of Corynebacterium capable of producing at high yield and conversion alpha,-omega-alkanedioic acid of 10 to 14 carbon atoms into a composition which has a pH of from 6 to 9 and which comprises 1 to 50 percent by volume of n-alkane of 10 to 14 carbon atoms and a complemental amount of the culture medium above; (2) maintaining the composition at a temperature of between about 20° to 45°C. for 48 to 96 hours and (3) separating the alpha,omega-alkanedioic acid from the resulting mixture.

In the recitation of the process above it is stated that the Corynebacterium mutant is capable of producing at high yields and conversions the alpha,omega-alkanedioic acid. When the process of this invention is utilized, this statement means to produce alpha,omega-alkanedioic acid at yields and conversions such that the percentage of the n-alkane converted to the alpha,omega-alkanedioic acid is at least 12.0 mole percent; preferably at least 19 mole percent. The amount of n-alkane converted to alpha,omega-alkanedioic acid (on a mole percent basis) following the process of the present invention ranged from 25 to 35 percent with some bacterium. This is calculated by multiplying the yield times the conversion. Conversion is defined as the percentage amount in moles of the n-alkane converted to other than the n-alkane without consideration as to what it is converted to while yield means the percentage amount in moles of the n-alkane converted which is in the form of the alpha,omega-alkanedioic acid. Normally when conversion is high, yield is lower and vice versa. Therefore, these can vary up and down but the product of the two is always greater than the above-recited percentages.

Some preferred mutated strains of the Corynebacterium are on file with the American Type Culture Collection (ATCC), 12301 Parklawn Drive, Rockville, Md. 20852. These strains are referred to throughout by their ATCC number.

The organism tentatively assigned to the genus Corynebacterium was first isolated by J. W. Foster (J. Bac-

teriology 85, 859 (1963). The original culture was pink but after a series of mutations with chemical and physical mutagens the culture lost the capability of producing a pigment. The organism is a nonmotile, gram (+) rod with metachromatic granules. Snapping division produces angular and palisade arrangement of cells. Older cells often lose gram (+) characteristic with granules still evident. The bacterium is in obligate aerobe and utilizes nitrates as sole source of nitrogen. The bacterium rods are 0.3 to 0.4 by 0.7 to 0.8 micron. They grow well on most common laboratory media, but grow better on the culture medium recited above. Colonies of bacteria on tryptone glucose agar are dry, granular and small. Optimum temperature of growth is 37°C.

The mixture inoculated by the Corynebacterium in the normal process comprises the composition, i.e., the n-alkane of 10 to 14 carbon atoms and the culture medium as discussed above and the inducer, i.e., the blend of substantially branched saturated aliphatic hydrocarbons of 12 to 22 carbon atoms and/or a blend of n-alkanes of 15 to 24 carbon atoms. Normally, the Corynebacterium mutant is added as part of an inoculum as is described above. This inoculum is usually initially present in the reactor vessel at about 5 to 20 percent by volume of the composition, inoculum and inducer.

The pH of the mixture of the n-alkane of 10 to 14 carbon atoms, culture medium and inducer should be from 6 to 9 initially with the preferred range being from 7 to 8. The most preferred range is from 7 to 7.5. The temperature of the contents of the reactor vessel should be from 20° to 45°C. both at the time the bacterium is added and during fermentation. The preferred range is 25° to 35°C. The fermentation is normally continued for up to 96 hours. High yields and conversions are not obtained until about 48 hours and after 72 hours diminishing returns set in.

One method of separating the alpha,omega-alkanedioic acid from the resulting mixture is to (1) remove the cells and excess hydrocarbon from the phase by phase separation, (2) adjust the pH of the aqueous layer to 2.0 with concentrated sulfuric acid, (3) filter out the precipitate, (alpha,omega-alkanedioic acid) and (4) wash precipitate with water. The purity of the acid is normally 50 to 65 percent by weight when this procedure is followed.

Mutants of the Corynebacterium which are useful in the process can be prepared by the standard techniques of (1) high energy radiation; (2) chemical mutation; (3) lethal synthesis and combinations thereof. The two former techniques are preferred. The mutants referred to herein were prepared by one or a combination of these three methods.

The process is useful in preparing the alpha,-omega-alkanedioic acid. The acids are useful as intermediates in the preparation of polyamides which have low water absorption and good stiffness and which can be formed into fibers.

The following Examples are meant to illustrate but not to limit the invention. Parts and percentages are by weight unless otherwise specified.

EXAMPLE I

Molasses yeast broth having the following composition was prepared:

0.15 weight/volume percent of K_2HPO_4 ,
0.06 weight/volume percent of $NaH_2PO_4 \cdot H_2O$,

5 weight/volume percent of cane molasses,
0.5 weight/volume percent yeast extract, and
remainder - water.

The molasses yeast broth was adjusted to a pH of 7.0 to 7.1 with NaOH, 60 ml. was transferred to a 300 ml. shaker flask and autoclaved for 15 minutes at 121°C. A loopful of cells of a mutant of *Corynebacterium* sp. G17B5 (ATCC 21747) from a fresh growth on a tomato juice agar slant was transferred to the sterile molasses yeast broth. The broth was incubated at 37°C. for 24 hours in a 1 inch throw rotary shaker at 220 rpm. This broth was used as an inoculum for 500 mls. of molasses yeast broth in a 2-liter shaker flask. The 2-liter shaker flask was incubated for 24 hours at 37°C. in a rotary shaker at 240 rpm. Contents of two of the 2-liter shaker flasks were utilized as the inoculum for a fermenter jar. The cell count in the inoculum was 3 × 10⁹ cells per ml. while the pH of the inoculum was 7.2.

The fermenter jars were prepared as follows:

To a 14-liter jar was added 2100 mls. of tap water; 40 grams sodium acetate; 20 grams tomato juice broth solids; 40 mls. of Ethofats, mono-fatty or rosin acid esters of polyoxyethylene glycols; 1,000 mls. dodecane; 1,000 mls. of "Soltrol" 170 (Phillips Petroleum Co.), a blend composed of substantially branched saturated aliphatic hydrocarbons of 14 to 22 carbon atoms boiling in the range of 196° to 250°C.; and 5,000 mls. of a doubly concentrated salts and buffer medium prepared as follows:

The following ingredients were added to the distilled water in their respective concentrations:

0.04 weight/volume percent $MgSO_4 \cdot 7H_2O$
0.3 weight/volume percent K_2HPO_4
0.12 weight/volume percent in an $Na_2HPO_4 \cdot H_2O$
5 weight/volume percent $NaNO_3$
0.003 weight/volume percent $CaCl_2$

	Stock Solution Concentration
0.2 volume percent of stock solution $FeSO_4$ containing ethylenediamine tetraacetic acid chelating agent	0.125 g/100 mls.
0.2 volume percent of stock solution $MnSO_4 \cdot H_2O$	80 mgs/100 mls.
0.2 volume percent of stock solution H_3BO_3	5 mgs/100 mls.
0.2 volume percent of stock solution $Na_2MoO_4 \cdot 2H_2O$	43 mgs/100 mls. 0.2 volume percent of stock
solution K1	20 mgs/100 mls.
0.2 volume percent of stock solution $ZnSO_4 \cdot 7H_2O$	80 mgs/100 mls.

The pH of the salts and buffer medium was adjusted to 7.1 to 7.2 with NaOH.

The fermenter jars were autoclaved for 60 minutes at 128°C. with hose lines and cotton plugs added where needed and then cooled. The inoculum was then poured into the cooled sterile fermenter medium. The fermenter (New Brunswick Model F-14) was equipped with an impeller which had a speed of 550 rpm. The temperature in the fermenter was 30°C. Sterile filtered air was introduced at the rate of 10 liters per minute into the fermenter. The fermenter was operated under these conditions for 91 hours. The millimoles of dodecanedioic acid produced per liter of reactants in the fermenter was 97.8 (gas chromatography). The percent (mole) conversion was 77 and the percent (mole) yield was 33.

EXAMPLE II

A loopful of *Corynebacterium* sp. 234-30 (ATCC 21745) cells was transferred from a two-day agar slant growth on tomato juice agar to molasses yeast broth (50 mls. in a 300 ml. shaker flask) prepared as in Example I. The broths were incubated for 24 hours at 37°C. in a 1 inch throw rotary shaker at 220 rpm and used as an inoculum to second stage broth (10 volume percent inoculum equals 25 mls. to 250 mls. fresh molasses yeast broth in one liter shaker flask). Second stage broth was incubated for 27 hours at 37°C. in a liter shaker flask at 240 rpm. This then was used as the inoculum to the main fermentation media test flask.

The main test flasks were prepared as follows: doubly concentrated salts and buffer medium prepared as in Example I, was diluted to 65 percent of its original concentration with distilled water. To this medium was added 0.3 weight/volume percent tomato juice broth

20 solids and 0.5 weight/volume percent sodium acetate. 20 Mls. of this solution was measured into 300 ml. shaker flask with 0.1 ml. Ethofats emulsifier, 2.5 mls. n-dodecane and 2.5 mls. Soltrol 170 (a blend of substantially branched saturated aliphatic hydrocarbons of 14 to 22 carbon atoms, boiling point 196° to 250°C.). The flasks were autoclaved after being gauze covered.

5 Mls. of the second stage broth were added to each test flask. The test flasks were incubated at 30°C. for three days on a rotary shaker at 220 rpm; the rotary

30 shaker having a 1 inch throw. After the incubation period all the flasks were adjusted to the initial volume with distilled water. 10 ml. samples were centrifuged for separation of the residual hydrocarbon cells and the aqueous fractions. The cells were between the oil and 35 aqueous phases. Dodecanedioic acid assay of the aqueous layer was done by a thin layer chromatography. The results were that 67 millimoles of dodecanedioic acid were produced per liter of reactants in the test flask. The yield was 38 percent (mole) and conversion 40 was 50 percent (mole).

EXAMPLE III

Following the procedure of Example II, 1,12-dodecanedioic acid was prepared from dodecane in the 45 presence of Soltrol 170 (same as in Example II) using the bacteria shown in Table I. The results of the runs are shown in Table I.

We claim:

1. In a process for the production of alpha,omega-alkanedioic acid of 10 to 14 carbon atoms in a mixture comprising n-alkane of 10 to 14 carbon atoms, culture medium and a mutant of *Corynebacterium* capable of producing alpha,omega-alkanedioic acid at high yield and conversion, the improvement which comprises operating the process in the presence of an inducer selected from the class consisting of a blend comprising substantially branched saturated aliphatic hydrocarbons of 12 to 22 carbon atoms, the blend having a boiling point of from 150° to 255°C., a blend comprising n-alkanes having from 15 to 24 carbon atoms and mixtures thereof with the proviso that initially the ratio of the volume of the inducer to the n-alkane of 10 to 14 carbon atoms is from 3:1 to 1:3 and the volume of n-alkane of 10 to 14 carbon atoms is from 1 to 50 per-

cent by volume of the total volume of the culture medium and n-alkane of 10 to 14 carbon atoms.

2. The process of claim 1 in which the inducer is a blend comprising substantially branched saturated aliphatic hydrocarbons which comprises hydrocarbons of 14 to 22 carbon atoms and which has a boiling point of from 196° to 250°C.

3. The process of claim 2 in which the ratio of the volume of the inducer to the n-alkane of 10 to 14 carbon atoms is about 1:1.

4. The process of claim 3 in which the volume of n-alkane of 10 to 14 carbon atoms is 5 to 20 percent of the total volume of the culture medium and n-alkane of 10 to 14 carbon atoms.

5. The process of claim 4 in which the n-alkane of 10 to 14 carbon atoms is of 12 carbon atoms.

6. The process of claim 1 in which the process to which the improvement is made comprises 1) introducing a mutated strain of *Corynebacterium* capable of producing at high yield and conversion alpha,omega-alkanedioic acid of 10 to 14 carbon atoms into a composition which has a pH of from 6 to 9 and which comprises 1 to 50 percent by volume of n-alkane of 10 to 14 carbon atoms and a complemental amount of culture medium; 2) maintaining the composition at a temperature of between about 20° to 45°C. for 48 to 96 hours; and 3) separating the alpha,omega-alkanedioic acid from the resulting mixture.

7. The process of claim 5 in which the culture medium is an aqueous culture medium comprising (1) 3 to 35 grams per liter of a member selected from the class consisting of alkali metal nitrate, calcium nitrate, magnesium nitrate, strontium nitrate, beryllium nitrate and mixtures thereof; (2) 0.3 to 10 grams per liter of alkali metal phosphate; (3) 1 to 15 grams per liter of a member selected from the class consisting of alkali metal acetate, calcium acetate, magnesium acetate, strontium acetate, beryllium acetate and mixtures thereof; and (4) a nutrient source.
